United States Patent Office.

A. W. WILCOX, OF NEW HAVEN, CONNECTICUT.

Letters Patent No. 77,428, dated April 28, 1868.

IMPROVEMENT IN BELLOWS FOR REED MUSICAL INSTRUMENTS.

The Schedule referred to in these Letters Patent and making part of the same.

TO ALL WHOM IT MAY CONCERN:

Be it known that I, A. W. Wilcox, of New Haven, in the county of New Haven, and State of Connecticut, have invented a new Improvement in Bellows for Reed-Instruments; and I do hereby declare the following, when taken in connection with the accompanying drawings, and the letters of reference marked thereon, to be a full, clear, and exact description of the same, and which said drawings constitute part of this specification, and represent, in—

Figure 1, a transverse section, the exhaust expanded; and, in

Figure 2, a transverse section, the exhaust compressed in its natural position.

This invention relates to an improvement in the construction of bellows for that class of instruments in which the reeds are operated by exhausting the air from the wind-chest, the air entering through the reeds to supply the exhaustion.

Heretofore, in this class of bellows, the valves have been placed upon the under side of the reservoir, and thus depended entirely upon the draught of the vacuum created in the reservoir to close the valves, the valves, by their natural inclination, always lying open. This construction necessitates no inconsiderable loss of power.

The object of my invention is, first, to overcome this difficulty, and consists in the arrangement of a valve-chamber within the reservoir, through the perpendicular wall of which the openings are formed, and valves hung thereon, so that, by their own gravity, their natural position is to be closed. In this class of bellows also, the valves in the exhaust are placed upon the outer surface of the collapsing side. The lower side or floor of the exhaust, in its natural position, rests close up against the under side of the floor of the reservoir, the collapsing side, with the valves thereon, being folded between the two. This construction necessitates a short movement, at least of the floor of the exhaust, before it can commence to operate or have any effect upon the reservoir, thus necessitating a loss of time and power at this point.

The further object of my invention is to overcome this difficulty, and therefore consists, second, in forming a channel or a raised edge upon the upper side of the floor of the exhaust, so as to leave a space between the collapsed side or valves and the floor, so that the bellows will commence to operate upon the first start of the exhaust.

To enable others to fully understand my improvement, I will proceed to describe the same as illustrated in the accompanying drawings.

A is the wind-chest. B, the reservoir, formed by the floor C, hinged at the point *a*, the opposite side, *b*, being the collapsing side, the edge or space between the wind-chest and floor, C, being covered by a flexible material in the usual manner. D is the valve-chamber, formed in the reservoir by the arrangement of a wall, E, having openings, *e*, sufficient in number, (or its entire length,) from the reservoir into the chamber D; and upon the surface of the wall, in the chamber D, are arranged valves, *d*, so as to open outward from the exhaust, the valve-chamber D opening directly into the exhaust-chamber F, as seen in fig. 1. G is the floor of the exhaust, hinged to the floor, C, of the reservoir at *g*, the edge between the two floors enclosed by a flexible material, so as to collapse, as seen in fig. 2, or expand, as in fig. 1. The natural position of the floor G is as seen in fig. 2. Through the collapsing side, *f*, are formed several openings, more or less in number, provided with valves, *h*, upon the outside, opening outward.

If the two floors were formed of an equal thickness in the usual manner, the collapsing of the exhaust, as in fig. 2, the floor of the exhaust would close the openings in the side, *f*, before the collapse had completely taken place, thus leaving a portion of compressed air within the exhaust. This would necessitate a movement downward of the floor G before the exhaust would begin to operate upon the reservoir. To obviate this, I form a recess, *n*, in the floor G, either by cutting away a part of the floor, as seen in the drawings, or by constructing a ledge, *m*, upon the edge of the floor, so as to leave a space beneath the valve *h* when closed; therefore the air in the exhaust can escape through the valves until the exhaust is completely collapsed, and the first start or

downward movement of the floor G will commence an instant action upon the reservoir by exhausting the air therefrom through the valves *d* to supply the increasing exhaust-chamber.

By this construction, I have overcome, in a very simple manner, the two difficulties which I have mentioned.

Having thus fully described my invention, what I claim as new and useful, and desire to secure by Letters Patent, is—

1. The arrangement of the valve-chamber D within the reservoir B, by the construction of the wall E therein, with the openings *e* and valves *d* thereon, substantially in the manner and for the purpose specified.

2. The construction of a recess in the floor G of the exhaust, beneath the openings *f*, substantially in the manner and for the purpose described.

A. W. WILCOX.
